UNITED STATES PATENT OFFICE.

FRANK W. ROBINSON, OF READING, PENNSYLVANIA, ASSIGNOR TO SCHUYLKILL HOSIERY MILLS, INC., OF READING, PENNSYLVANIA, A CORPORATION OF PENNSYLVANIA.

YARN-CHANGE BINDER FOR CIRCULAR-KNITTING MACHINES.

Application filed May 1, 1923. Serial No. 635,839.

To all whom it may concern:

Be it known that I, FRANK W. ROBINSON, a citizen of the United States, residing at Reading, county of Berks, State of Pennsylvania, have invented a new and useful 5 Yarn-Change Binder for Circular-Knitting Machines, of which the following is a specification.

My present invention comprehends a novel 10 construction and arrangement of a yarn change binder for circular knitting machines of the type in which a revolving cylinder is employed.

In machines of this type, as ordinarily 15 constructed, the binder is hung in the center of the cylinder. One of the objects of my present invention is to devise a novel construction of a yarn change binder which is constructed and arranged in such a manner 20 that the space in the center of the cylinder, which is ordinarily taken up by the binder, will be left free so that it can be utilized for other purposes.

It further comprehends a novel construction 25 of a yarn change binder wherein a hook is directly suspended over the yarn which is out of knitting action, and, when a change of yarn is to take place, the yarn finger drops and holds the yarn which is being 30 fed on the outer circle of the needles. The hook is so pivoted that it holds the other end of the same yarn at the inner circle to cause it to lie across the path of the needle.

When the yarn is knitted in, the binder 35 drops, it then opens and the yarn is then released. The binder is now in a position to receive the yarn which is to come out of knitting action. The yarn finger which carries such yarn first rises to such a position 40 that the yarn is brought out of its knitting position. Thereafter the binder closes and the yarn is severed.

It further comprehends novel yarn positioning mechanism, yarn binding mechanism, 45 yarn severing mechanism and means for occasioning the cyclical operation of said mechanism.

Other novel features of construction and advantage will hereinafter more fully 50 appear in the detailed description and the appended claims.

For the purpose of illustrating my invention, I have shown in the accompanying drawings a typical embodiment thereof

which is at present preferred by me, since 55 this embodiment will be found in practice to give satisfactory and reliable results. It is, however, to be understood that the various instrumentalities of which my invention consists can be variously arranged and organized and that my invention is not limited to the precise arrangement and organization of these instrumentalities as herein shown and described.

Figure 1 represents, in side elevation, a 65 portion of a circular knitting machine in conjunction with which yarn change binders, embodying my invention, are employed.

Figure 2 represents, in front elevation, the 70 yarn change binder and certain of its adjuncts.

Figure 3 represents a top plan view of the 75 yarn change binder.

Figure 4 represents a section on line 4—4 of Figure 3.

Figure 5 represents, in side elevation and in detached position, a portion of the 80 yarn severing and binding mechanism.

Figure 6 represents a section on line 6—6 of Figure 5.

Figure 7 represents, in detached position, 85 a top plan view of the hook and the shaft which carries it.

Figure 8 represents diagrammatically the 90 relative position of certain parts of the yarn change binder when one yarn is in the binder and the other yarn is in knitting action.

Figure 9 represents diagrammatically the 95 relative position of certain of the parts when one yarn is in knitting action and the other yarn has just been brought into knitting action.

Figure 10 represents diagrammatically the 100 relative position of certain of the parts when both yarns are in knitting action and the binder is open to release the new yarn which is to be knitted in.

Figure 11 represents diagrammatically the 105 relative position of the parts shown in Figures 8, 9 and 10, when one yarn is in knitting action and the other yarn is out of knitting action and in position to be received by the binder.

Similar numerals of reference indicate 110 corresponding parts.

Referring to the drawings,

1 designates any usual or conventional type of circular knitting machine, the con-

struction and operation of which are well known to those skilled in this art. 2 designates the conventional latch ring on which the working parts of the yarn change binder 5 are mounted. 3 designates a yarn change binder, embodying my invention. The yarn change binder has its working parts supported in and carried by a bracket 4 which is secured to the latch ring by means of 10 fastening devices 5. 6 designates a rod fixed in the bracket 4 and on which is loosely mounted a lever 7 which is provided with the hubs 8, see Figure 2, the functions of which are to serve as spacing members. 15 The lever 7 is provided intermediate its ends with a depending enlargement having the operative cam face 9 with which co-operates the forward end of a lever 10 which is fulcrumed at 11 to a stationary portion 20 of the machine frame. The lever 10 has connected with it a rod 12 which is also connected to a lever 13 suitably fulcrumed and controlled by a cam 14 carried by the conventional pattern drum of a circular 25 knitting machine. The lower end of the lever 7 forms a clamping or binding member 15. The lower end of the lever 7 is bifurcated to provide a knife 16 having a cutting edge 17. 18 designates a movable 30 knife which is pivoted at 19 between the binder 15 and the knife 16, and it is bevelled off to form the cutting edge 20, see Figure 6. The knife 18 is provided at its upper end with the longitudinally extending slot 35 21 into which extends a pin 22 carried by an adjusting arm 23 which is provided with a slot 24 through which is adapted to pass the fastening devices 25 which engage the arm 26 secured to the bracket 4 in any 40 desired manner. It will thus be seen that the arm 23 can be adjusted to vary the action of the knife. The lever 7 is normally maintained in its downward position by means of a spring 27 one end of which is fixed to said lever 7, as at 28. For purpose 45 of illustration, I have shown this spring as encircling the hub 8 and its free end bears against a stationary portion of a bracket 4. The upper end of the lever 7 is provided 50 with a bevelled or cam face 29 against which is adapted to bear the forward end of a manually actuated lever 30 which is fulcrumed at 31 to the bracket 4. By moving lever 30 toward the right in Fig. 4 the lower 55 end thereof is caused to abut against cam face 29 and through the instrumentality of lever 7 hold the binder 3 in raised position so that the loose end of thread is held in said binder. 60 32 designates an arm which is fixed to a sleeve 33 which is loosely mounted on a rod 34. The forward end of the arm 32 forms a depending hook 35. The arm 32 is provided with a laterally extending member 65 36 which overhangs the yarn fingers 37 and

38 which are loosely mounted on the rod 39, and each is normally maintained in its downward position by means of springs 40. The downward movement of the yarn fingers 37 and 38 is limited in the usual manner by 70 the throat plate 41. The sleeve 33, see Figure 2, is provided with a tension device in the form of a spring 42, one end of which is connected with said sleeve, which is slotted to receive it, and the opposite end of such 75 spring is connected to a stationary portion of the machine.

The operation will now be readily apparent to those skilled in this art and is as follows:—

It is common in machines of this type to change from one type of yarn to another, for example, from silk to cotton and from cotton to silk. It will thus be understood that the yarn finger 37 receives one type of 85 yarn and the yarn finger 38 another type.

Referring now more particularly to the diagrammatic views seen in Figures 8 to 11 inclusive, I have shown in Figure 8 the position which the parts assume when the yarn 43 co-operating with the yarn finger 38 is in knitting action, while the yarn finger 37 has its yarn 44 out of knitting action and its free end is held in the binder.

The yarn fingers 37 and 38 are actuated in the usual manner such as is well known in the art and I have therefore deemed it unnecessary to describe and illustrate in detail the construction for operating these 90 yarn fingers. In the first position illustrated in Figure 8, the yarn finger 37 is in its raised position while the yarn finger 38 is in its down position. The yarn finger 37 is moved downwardly from its position seen in Figure 8 into that seen in Figure 9, and as the hook 35 is held in its raised position by one of the fingers, the hook 35 will drop when both yarn fingers are down and will be in the position seen in Figure 9, so that the hook 35 will receive 100 the yarn 44 which is still held in the binder. In the next position seen in Figure 10, the yarn fingers 37 and 38 are both down as well as the hook 35 controlled by them. The binder is also in its down position and has 110 released the yarn 44 which is now in knitting action as well as the yarn 43.

In the next stage of the operation, the 115 yarn finger 38 is down while the yarn finger 37 is up, thereby holding up the hook 35. The yarn finger 37 has drawn the yarn 44 out of the path of the knitting action and into the binder ready to be clamped therein.

In the next stage of the operation, the 120 knife 18 moves upwardly thereby severing the yarn 44, and clamping it between the knife 18 and the binder 15.

It will be understood that the cam 14 through the lever 13 and rod 12 causes the 125 lever 7 to be raised and lowered at the 130

proper times. The opening and closing of the knife 18 is caused by the movement of the lever 7, since the knife 18 is provided with a cam slot 21 into which extends the 5 pin 22 so that, as will be apparent, the upward movement of the lever 7 on its fulcrum causes the knife 18 to close and the downward movement of such lever causes the knife 18 to open.

10 It will be apparent that the action just described with relation to the yarn 44 takes place in a similar manner with respect to the yarn 43 at the proper time so that either yarn, at will, depending upon the adjustment of the machine, can be brought into or out of knitting action. If the latch ring were raised, the binder would drop unless some means are provided for locking it in position, and, for this purpose, I provide 15

20 the manually actuated lever 30 which will retain the binder in its raised position so that the loose end of the thread will be held in the binder.

It will now be apparent that I have devised a novel and useful yarn change binder for circular knitting machines which embodies the features of advantage enumerated as desirable in the statement of the invention and the above description, and while 25 I have, in the present instance, shown and described an embodiment thereof which will give in practice satisfactory and reliable results, it is to be understood that this embodiment is susceptible of modification in 30 various particulars without departing from the spirit or scope of the invention or sacrificing any of its advantages.

Having thus described my invention, what I claim as new and desire to secure 40 by Letters Patent, is:

1. A yarn change binder, comprising a hook suspended over the yarn which is out of knitting action, a plurality of yarn fingers and their actuating means, said yarn 45 fingers controlling the movement of said hook, and automatically actuated yarn binding and cutting mechanism.

2. A yarn change binder, comprising in combination with the needle cylinder, of a hook pivotally supported to be suspended over the yarn which is out of knitting action, the yarn fingers and their actuating means, said yarn fingers controlling the position of said hook, and automatically controlled yarn severing and binding mechanism.

3. A yarn change binder, comprising in combination with the yarn fingers and their actuating means, of a hook movably mounted at one end and provided with a laterally

extending arm to overhang the yarn fingers, yarn severing and binding mechanism, and pattern controlled means for actuating said yarn severing and binding mechanism.

4. A yarn change binder, comprising in 65 combination with the yarn fingers and their actuating means, of a hook pivotally carried and having means overhanging said yarn fingers, a lever having a bifurcated end, a knife movably mounted in said end 70 and contributing therewith to form yarn binding and severing mechanism, and pattern controlled means to actuate said lever.

5. A yarn change binder, comprising in 75 combination with the yarn fingers and their actuating means, of a hook pivotally mounted at its rear end and provided with means to overhang said fingers, a lever having its free end bifurcated, a knife movably carried in said bifurcated end, contributing 80 therewith to form a cutter and a binder and provided with a slot, a fixed member extending into said slot to effect the opening and closing movement of said knife when said lever is moved, resilient means to move said 85 lever in one direction, and pattern controlled means to move said lever in an opposite direction.

6. A yarn change binder, comprising in 90 combination with the yarn fingers and their actuating means, of a hook pivotally mounted at its rear end and provided with means to overhang said fingers, a lever having its free end bifurcated, a knife movably carried in said bifurcated end, contributing 95 therewith to form a cutter and a binder and provided with a slot, a pin adjustably mounted and extending into said slot to cause the proper movement of said knife during the movement of said lever, resilient 100 means to move said lever in one direction, and pattern controlled means to effect the movement of said lever in a reverse direction.

7. A yarn change binder, comprising in 105 combination with the yarn fingers and their actuating means, of a hook adapted to be raised by one or the other of said yarn fingers, a lever, a knife co-operating therewith to form yarn binding and yarn severing mechanisms, resilient means to move said lever in one direction, pattern controlled means to move said lever in a reverse direction, and manually actuated 110 means to lock said lever in an inoperative 115 position.

FRANK W. ROBINSON.
